CLAIM

The ornamental design for a “ticket terminal,” as shown and described.

DESCRIPTION

FIG. 1 is a perspective view of a ticket terminal in accordance with my new design;

FIG. 2 is a front elevational view thereof;

FIG. 3 is a rear elevational view thereof;

FIG. 4 is a rotated top view thereof, in a 30° clockwise direction;

FIG. 5 is a bottom plan view of the ticket terminal of FIG. 1;

FIG. 6 is a right side elevational view thereof; and,

FIG. 7 is a left side elevational view thereof.

In the drawings, the letter ‘Q’ shown in broken lines forms no part of the claimed design.
